SHOESHINE OUTFIT

Frank Burger, Flushing, N. Y.

Application May 8, 1943, Serial No. 486,135

5 Claims.

(Cl. 15—265)

This invention relates to new and useful improvements in a shoe shine outfit.

More specifically, the invention contemplates a shoe shining outfit which is characterized by a suitcase-like container having a container body and a hinged top cover and within which certain parts of the outfit are mounted.

The invention contemplates the use of support strips attached on the inner faces of the side walls of said container body and top cover for fixedly supporting a platform across the top of said container body in a closed position of the cover. The invention contemplates that a shoe shine foot rest be mounted on said platform. Furthermore, it is proposed that a partition for supporting shoe polish boxes and brushes be mounted across said container body spaced down from the top thereof. It is proposed to so proportion and arrange the parts that the shoe polish boxes, brushes and other articles of the shoe shine outfit will all maintain their positions even when the suitcase is being held by a side handle and carried about in a closed condition.

The invention also contemplates a modified form with means for supporting said platform in an elevated position above the top of said container body so that the shoe polish boxes and brushes within the container body supported by said partition are readily accessible.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a shoe shine outfit constructed in accordance with this invention, and illustrated in a closed position.

Fig. 2 is a perspective view of the shoe shine outfit in an open position.

Fig. 3 is a plan view of Fig. 2 but illustrated with certain of the parts in a different position.

Fig. 4 is an elevational view looking in the direction of the line 4—4 of Fig. 3.

Fig. 5 is a plan view similar to Fig. 4 but illustrated with the top platform removed.

Fig. 6 is a sectional view as though taken on the line 6—6 of Fig. 5 but illustrated with the top platform in position.

Fig. 7 is a fragmentary enlarged detailed view of a portion of Fig. 5.

Fig. 8 is a sectional view similar to Fig. 6 but illustrating a modified form of the invention.

Fig. 9 is a horizontal sectional view taken on the line 9—9 of Fig. 8.

Fig. 10 is a fragmentary vertical sectional view taken on the line 10—10 of Fig. 9.

Fig. 11 is a perspective view of a portion of Fig. 9.

Fig. 12 is a perspective view of one of the support strips used in the device.

The shoe shine outfit, according to this invention, includes a suitcase-like container 15 having a container body 16 and a hinged top cover 17. The cover 17 is hingedly connected to the body 16 at one side by the hinges 18. A handle 19 is mounted on the outside of the container body 16 on the side directly opposite to the side provided with the hinges 18. Latches 20 are also mounted upon the sides of the container 16 and the cover 17 for locking these parts together.

20 A plurality of support strips 21 are attached on the inner faces of the side walls of said container body 16 and also on the inner face of the side walls of said container top cover 17. These support strips 21 are for the purpose of supporting a platform, such as the platform 22, across the top of the container body 16 in the closed position of the said cover 17. Each of the support strips 21 is in the nature of a semi-cylindrical strip, preferably obtained by cutting 25 dowel pins down their centers. These strips 21 are formed with grooves in which small holding strips 23 are mounted. The holding strips 23 also engage corresponding grooves in the faces of the side walls of the container body 16 in 30 the top cover 17 for securely holding the support strips 21 in position.

The platform 22 is merely rested on the top ends of the support strips 21 which are located within the container body 16. It is pointed out 35 that when the top cover 17 is closed the support strip 21 which are mounted on the top cover will engage the top face of the platform 22 firmly holding it in position. However, when the top cover 17 is in its open position, the platform 22 40 may be removed.

The platform 22 is provided with a shoe shine foot rest 25. The particular foot rest illustrated is formed from two sections, a base section 26 which is permanently attached on the top face 45 of the partition 16 and a top section 27 which is hingedly mounted on the base section 26. Latch means 28 operate between the sections 26 and 27 and are capable of latching these sections in vertical aligned positions, as shown for example in 50 Fig. 4. When the latch means 28 is opened the 55

top section 27 may be pivoted downwards. In this latter position, the top cover 17 may be closed and the bottom face of the top cover will engage against and hold the top section 27 in its downwardly folded position. A pair of spaced handles 29 is also mounted on the top face of the platform 22 by which the platform may be easily gripped and removed when desired. Several holding strips 30 are also mounted on the top face of the platform 22 and normally hold rolls of cloth 31 which may be used to polish one's shoes. These strips 30 are in the nature of semi-circular strips beneath which the rolls 31 are merely slipped.

A partition 32 is fixedly mounted across said container body 16 and is spaced downwards from the top thereof. This partition 32 is for the purpose of supporting shoe polishes and brushes. More specifically, it is formed with several openings 33 so that shoe polishing brushes may be engaged through these openings and rested against the bottom or other support within the container body 16.

The top face of the partition 32 is also formed with recesses 35 to accommodate shoe polish boxes 36. Other supporting elements are also located on the top of the partition 32 so as to prevent shifting of the objects supported thereon. For example, these elements may be in the nature of small strips 37 mounted on the top face of the said partition 32. The partition 32 is also formed with several relatively small openings 38 through which the bristle portions of shoe polish dabbers 39 are mounted. Several small pegs 40 project from the top face of the partition 32 and engage the sides of the dabbers 39 to hold them from shifting.

The operation of the device is as follows:

The shoe shining outfit may be stored away when the top cover 17 is in its closed position, as shown in Fig. 1. In this condition it may also be easily transported. The outfit is used by opening the top cover 17, as illustrated in Fig. 2. The top section 27 of the shoe shine rest 25 is then swung up to its vertical position and thus latched, as illustrated in Figs. 3 and 4. The platform 22 may now be lifted off the container body 16 and the various brushes, dabbers and shoe polishes may be removed. The top platform 22 is then reset in position and one may rest one's foot on the shoe shine rest 25 and polish one's shoes, or, some other person may actually do the polishing.

In Figs. 8 to 12, a modified form of the invention is shown which is very similar to the prior form, distinguishing in that means have been associated with the platform 22 by which it may be elevated above the top of the container body 16 so that one may reach in between the elevated platform 22 and the top of the container body 16 and remove the various brushes, dabbers and shoe polishes stored upon the platform 32. More specifically, the platform 22 is provided with a plurality of supported legs 42. These legs have top lugs 43 by which fastening elements 44 attach them to the bottom face of the platform 22. The legs 42 slidably extend through slits or other openings 45 formed in the support strips 21'. These support strips 21' have top lips 46 cooperative with bottom projections 47 which limit the amount to which the platform 22 may be raised.

Certain of the support strips 21' are provided with bolts 48 for latching the projections 47 in

elevated positions. These bolts 48 are mounted on strips 49. The strips 49 are supported on rods 50 engaging through the side walls of the container body 16. Handles 51 are mounted on the outer ends of the rods 50. Springs 52 normally urge the rods 50 outwards. This indirectly resiliently urges the bolts 48 into operative positions.

The operation of this form of the invention is substantially identical to the prior form, distinguishing in the fact that the platform 22 may be elevated to the dot and dash line position 22' illustrated in Fig. 8. To do this the handles 29 are gripped and the platform 22 is lifted by these handles.

The projections 47 will cam past the bolts 48 which immediately engage beneath said projections 47 and latch the legs 42 and consequently the platform 22 in an elevated position. It is now possible to reach in between the legs 42 and reach the brushes, the polish and the other articles on the partition 32. The platform 22 may be lowered by pressing the handles 51 inwards. This indirectly moves the bolts 48 to release the projections 47. Now the platform 22 is free to move downwards.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A shoe shining outfit, comprising a suitcase-like container having a container body and a hinged top cover, support strips attached on the inner faces of the side walls of said container body and top cover for fixedly supporting a platform across the top of said container body in the closed position of said cover, a platform corresponding to the cross sectional shape of said body supported across the top of said container body by said support strips, a shoe shine foot rest mounted on said platform, and a partition for supporting shoe polish and brushes and mounted across said container body spaced down from the top thereof.

2. A shoe shining outfit, comprising a suitcase-like container having a container body and a hinged top cover, support strips attached on the inner faces of the side walls of said container body and top cover for fixedly supporting a platform across the top of said container body in the closed position of said cover, a platform supported across the top of said container body by said support strips, a shoe shine foot rest mounted on said platform, and a partition for supporting shoe polish and brushes and mounted across said container body spaced down from the top thereof, said support strips being in the nature of semi-cylindrical strips having their flat sides engaging said faces.

3. A shoe shining outfit, comprising a suitcase-like container having a container body and a hinged top cover, support strips attached on the inner faces of the side walls of said container body and top cover for fixedly supporting a platform across the top of said container body in the closed position of said cover, a platform supported across the top of said container body by said support strips, a shoe shine foot rest mounted on

said platform, and a partition for supporting shoe polish and brushes and mounted across said container body spaced down from the top thereof, said support strips being in the nature of semi-cylindrical strips having their flat sides engaging said faces, and reinforcement strips being engaged between said support strips and said faces to hold these support strips in position.

4. A shoe shining outfit, comprising a suitcase-like container having a container body and a hinged top cover, support strips attached on the inner faces of the side walls of said container body and top cover for fixedly supporting a platform across the top of said container body in the closed position of said cover, a platform supported across the top of said container body by said support strips, a shoe shine foot rest mounted on said platform, a partition for supporting shoe polish and brushes and mounted across said container body spaced down from the top thereof, and means for supporting said platform in an elevated position above the top of said container body, comprising support strips mounted upon the bottom face of said platform and slidably engaging grooves in

said support strips, and means for holding the second-named strips in elevated positions.

5. A shoe shining outfit, comprising a suitcase-like container having a container body and a hinged top cover, support strips attached on the inner faces of the side walls of said container body and top cover for fixedly supporting a platform across the top of said container body in the closed position of said cover, a platform supported across the top of said container body by said support strips, a shoe shine foot rest mounted on said platform, a partition for supporting shoe polish and brushes and mounted across said container body spaced down from the top thereof, and means for supporting said platform in an elevated position above the top of said container body, comprising support strips mounted upon the bottom face of said platform and slidably engaging grooves in said support strips, and means for holding the second-named strips in elevated positions, and including means for releasing the holding action so that said platform may again be lowered.

FRANK BURGER.
